(57) **CLAIM**

The ornamental design for a culinary blowtorch attachment, as shown and described.

DESCRIPTION

FIG. 1 illustrates a top, front, and left side perspective view of an embodiment of a blowtorch and attached culinary blowtorch attachment embodying a new design.

FIG. 2 illustrates a front view of the culinary blowtorch attachment of FIG. 1.

FIG. 3 illustrates a back view of the culinary blowtorch attachment of FIG. 1.

FIG. 4 illustrates a top view of the culinary blowtorch attachment of FIG. 1.

FIG. 5 illustrates a bottom view of the culinary blowtorch attachment of FIG. 1.

FIG. 6 illustrates a left side view of the culinary blowtorch attachment of FIG. 1.

FIG. 7 illustrates a right side view of the culinary blowtorch attachment of FIG. 1; and,

FIG. 8 illustrates a cross-sectional view of the culinary blowtorch attachment of FIG. 1, taken on cut plane 8-8 of FIG. 2.

The dash-dash broken lines in the drawings depict portions of the culinary blowtorch attachment that form no part of the claimed design.

1 Claim, 8 Drawing Sheets
